UNITED STATES PATENT OFFICE

173,259

ROBE

Max L. Cohen, Miami, Fla.

Application August 28, 1953, Serial No. 26,624

Term of patent 3½ years

(Cl. D3—26)

To all whom it may concern:

Be it known that I, Max L. Cohen, a citizen of the United States, residing at 6701 N. E. 2nd Court, Miami, Florida, have invented a new, original, and ornamental Design for a Robe, of which the following is a specification, reference being had to the accompanying drawing, forming a part hereof.

Fig. 1 is a front view of the robe, showing my new design.

Fig. 2 is a rear view of the robe shown in Fig. 1.

I claim:

The ornamental design for a robe, as shown.
